ACCELERATION RESPONSIVE SWITCHING CIRCUIT

Robert Ricardo Campbell, Baltimore, Md., assignor to Bendix Aviation Corporation, Towson, Md., a corporation of Delaware

Application September 28, 1956, Serial No. 612,858

5 Claims. (Cl. 123—32)

This invention relates to switching circuits and more particularly to such circuits employing transistors and operable with a time delay which varies in response to the magnitude and rate of the movement of a mechanical element.

It is an object of the invention to provide a transistor switching circuit of the above type which responds to accelerations of a mechanical element above a selected rate and which is simple and reliable.

This and other objects and advantages of the invention are realized by a transistor circuit including a relay in the collector circuit thereof and a capacitor in the base circuit which charges through the base to emitter resistance of the transistor in response to the variation of a resistor by movement of said mechanical element.

In the drawing:

Fig. 1 is a schematic diagram of a circuit embodying the invention and illustrating one use thereof; and

Fig. 2 is a perspective view of a portion of the intake manifold of an internal combustion engine, having associated therewith control elements of the circuit of Fig. 1.

In the drawing there is shown a shaft 1 which is driven in synchronism with the operation of an internal combustion engine and may be the distributor shaft thereof. Carried by the shaft 1 for rotation therewith is a lobed cam 2 having one lobe for each cylinder of the engine and driving, by means of a mechanical linkage 3, one contact element of a single pole, single throw switch 4. This contact is connected to a voltage reference plane indicated as the ground 5. The other contact is connected to a voltage reference plane indicated as the ground 5. The other contact is connected by way of a resistor 6 and a conductor 7 to the positive terminal 8 of a source of supply voltage which is shown as having a value of twelve volts conforming to the usual automobile battery.

The said other contact of the switch 4 is also connected to one terminal of a capacitor 10, the remaining terminal of which is connected to the conductor 7 by way of a resistor 11 and to the cathode of a diode 12. The anode of the diode 12 is connected to the base electrode of a transistor 13 and is further connected to the conductor 7 by way of a resistor 14 and to the voltage reference plane by way of a resistor 15.

The emitter electrode of the transistor 13 is connected to the emitter electrode of a second transistor 16 and their junction is connected by a resistor 17 to the conductor 7. The collector electrodes of transistors 13 and 16 are connected to the voltage reference plane by way of respective resistors 20 and 21. The collector of transistor 13 is also connected to the base electrode of transistor 16 by way of capacitor 22. The base electrode of transistor 16 is connected to the ground reference plane by way of resistor 23 and a variable resistor 24 in series.

The transistors 13 and 16 and their associated components form a monostable multivibrator, the output of which is taken from the collector electrode of transistor

2

16 and applied by way of a conductor 25 to an amplifier 26 and thence by way of a conductor 27 to a wiping contact element 30 carried by and insulated from an arm 31 which is mounted on the shaft 1 for rotation therewith. The contact element 30 sequentially wipes a plurality of contact segments 32 of which there is one for each cylinder of the engine. Only two of these are shown in the drawing. Each segment 32 is connected to one terminal of a solenoid coil 33 having an armature 34. The remaining terminal of each solenoid coil is connected to the voltage reference plane. The lower end of each armature terminates in a valve element 35 which seats in a valve seat 36 formed in the intake manifold of the internal combustion engine adjacent to the intake valve of a respective cylinder thereof.

The slider of the variable resistor 24 is mechanically connected by a linkage 37 to a piston 40 which is driven in response to the manifold vacuum of the engine. Connected across the terminals of the resistor 23 is a relay operated switch 41 which is normally in a closed position. The switch is operated by a relay coil 42, one terminal of which is connected to the voltage reference plane and the other terminal to the collector electrode of a transistor 43. The emitter electrode of this transistor is connected to the conductor 7 by the conductor 44. The base electrode is connected to the conductor 7 through a resistor 45. This electrode is also connected by way of a resistor 46 and a capacitor 47 in series to the movable contact 48 of a variable resistor 49 having one of its terminals connected to the conductor 7 and the other to the voltage reference plane. The movable contact 48 is driven through a mechanical linkage 50, 52 from the acceleration pedal 51 of the engine, which also controls the position of throttle valve 53 in the intake manifold 54, by way of linkage element 52 and crank arm 55.

In the operation of the device described above the switch 41 is opened and closed once while the contact element 30 is wiping each of the segments 32. When the switch is closed the upper contact, as illustrated, is placed at the voltage of the ground reference plane. When the switch is open it assumes the voltage of the terminal 8. This results in a voltage of square waveform as indicated at 52. The waveform 52 is differentiated by the elements 10 and 11 and the negative-going spikes of this differentiated waveform are applied through the low impedance of the diode 12 to the base electrode of the transistor 13.

Prior to the application of this triggering spike of voltage, the transistor 16 is conducting to saturation. The conduction of transistor 16 creates a voltage drop across the resistor 17 which results in a base to emitter current flow in transistor 13 sufficient to maintain that transistor cut off. In this situation the capacitor 22 will be charged, as indicated, charging through resistors 20 and 17 and the base to emitter resistance of transistor 16. When a negative trigger is applied to the base electrode of the transistor 13 a regenerative action occurs in which conduction is initiated in the transistor 13 resulting in a partial discharge of the capacitor 22 and a lessening of the conduction of transistor 16. This regenerative action culminates in the conduction of the transistor 13 to saturation and the cut off of transistor 16. The length of time during which transistor 16 will remain in the state of cut off is determined by the values of resistors 23 and 24, when both are in the circuit, but normally by resistor 24 alone.

The output of the multivibrator being applied through the amplifier 26, conductor 27, element 30 and segment 32 to one of the solenoid coils 33, lifts its armature 34, thus opening the valve 35 and allowing fuel under pressure to be injected through the valve.

The portion of the circuit, the operation of which has just been described, is disclosed in application Serial No. 608,798, filed September 10, 1956, in the name of Noble F. Pribble and entitled, "Driver Circuit for Fuel Injector." It is disclosed here to illustrate one use to which the invention may be put. The portion of the circuit, the operation of which will now be described, is the portion embodying the present invention.

The purpose of the instant invention is to switch an element into or out of a circuit by electronic means. The element so switched is illustrated here as the resistor 23 in the base circuit of transistor 16. As shown in the drawing, with the switch 41 in its closed state, the resistor 23 is out of the circuit. Under certain conditions of operation of a fuel injection control circuit, such as a sudden acceleration demand, it is desirable to provide a drastic increase in the duration of the multivibrator output pulse beyond that which would result from normal throttle action. This can be accomplished by inserting the resistor 23 into the circuit. This insertion is accomplished here in response to operation of the accelerator pedal 51 at a rate in excess in a selected value. The potentiometer 49 is connected to the pedal 51 by a linkage 50. The transistor 43 is normally cut off. When the pedal 51 is rapidly depressed, moving the slider 48 toward the voltage reference plane, the capacitor 47 charges with the polarity shown, through resistor 46 and the low base to emitter resistance of the transistor 43. The charging current from emitter to base causes collector current to flow which actuates the relay coil 42 and opens switch 41. This abruptly lengthens the duration of the output pulse of the multivibrator. The relay remains activated until the charging current flowing from the emitter to the base drops and causes the collector current also to drop.

A circuit with values as shown will allow the relay to be activated for two seconds when the slider 48 on resistor 49 is quickly moved over the length of the resistor. A very slow movement of the slider will not result in activation of the relay.

The values applied to the various components are for the purpose of indicating typical suitable values and should not be considered as restricting the invention.

What is claimed is:

1. Means for activating a relay in response to movement of a mechanical element in excess of a selected rate and maintaining its activation for a time which is a function of the magnitude and rate of said movement, comprising: a transistor, a relay coil in the output circuit thereof, an energy storage means in the input circuit thereof, means applying a D. C. potential to said storage element and means varying the magnitude of said potential in accordance with movement of said element.

2. Means for activating a relay in response to movement of a mechanical element in excess of a selected rate and maintaining its activation for a time which is a function of the magnitude and rate of said movement, comprising: a transistor, a relay coil in the collector circuit thereof, a capacitor in the base circuit thereof,

means applying a D. C. potential to said capacitor and means varying the magnitude of said potential as a function of the movement of said element.

3. Means for activating a relay in response to movement of a mechanical element in excess of a selected rate and maintaining its activation for a time which is a function of the magnitude and rate of said movement, comprising: a transistor, a relay coil in the collector circuit thereof, a capacitor in the base circuit thereof, means including a potentiometer applying a D. C. potential to said capacitor and a mechanical linkage between the slider of said potentiometer and said element.

4. A monostable multivibrator, means triggering said multivibrator into its unstable state and means for controlling the duration of said unstable state, comprising: an impedance element in an input circuit of said multivibrator, means short circuiting said element, a switch in the last named means, and operating means for said switch comprising a relay coil positioned to open said switch when activated, a transistor, means connecting said coil in an output circuit of said transistor, an energy storage element in an input circuit of said transistor, a movable element, means applying a D. C. potential to said storage element and means varying the magnitude of said potential in accordance with movement of said movable element.

5. In a system for injecting measured amounts of fuel into the cylinders of an internal combustion engine having an air throttle, said system including a solenoid operated valve for each cylinder of said engine, means applying fuel under constant pressure to said valves, and means opening said valves in synchronism with the operation of said engine; means controlling the duration of the open time of said valves, the last named means comprising: a monostable multivibrator, means triggering said multivibrator into its unstable state in synchronism with the operation of said engine, means applying the output pulses of said multivibrator sequentially to the respective solenoids of said valves and means controlling the duration of said output pulses, the last named means comprising a first impedance element in an input circuit of said multivibrator, means varying the impedance of said element as a function of the manifold vacuum of said engine, a second impedance element in an input circuit of said multivibrator, means normally short-circuiting said second impedance element, the last named means comprising a switch, a relay coil positioned to open said switch when activated, an amplifier circuit having input and output circuits, means connecting said relay coil in said output circuit of said amplifier, an energy storage element in said input circuit of said amplifier, means applying energy to said storage means, operating means for the air throttle of said engine and means varying the operation of said energy applying means in accordance with the movement of said air throttle operating means.
